The nature of the design and the application of the same will fully appear from the following description and the accompanying drawing, in which it is illustrated.

Referring to the drawing, A is the circular base or background, having the general appearance of a car-wheel. Within the rim of this wheel or circle the field is divided into three equal parts, B, C, and D. Within these spaces are pictorially represented the follow-

In the space C is the representation of a naked arm, with a chain or cord grasped in the hand and encircling the arm. In the field D is shown the ends of car-couplers and a hand extended 25 toward the link depending from one of them.

What I claim is—
